UNITED STATES PATENT OFFICE.

FRANK W. CALVERT, OF NARBERTH, PENNSYLVANIA, ASSIGNOR TO THE CHARLES E. Hires COMPANY, OF PHILADELPHIA, PENNSYLVANIA, A CORPORATION OF PENNSYLVANIA.

DESIGN FOR A LIQUID-DISPENSING FOUNTAIN.

44,555.

Specification for Design.

Patented Aug. 26, 1913.

Application filed May 2, 1911. Serial No. 624,674. Term of patent 14 years.

To all whom it may concern:

Be it known that I, FRANK W. CALVERT, a citizen of the United States, and a resident of Narberth, Montgomery county, Pennsylvania, have invented a certain new, original, and ornamental Design for a Liquid-Dispensing Fountain, of which the following is a specification, reference being had to the accompanying drawing, forming part thereof, showing a perspective view illustrating my design for a liquid-dispensing fountain.

This design comprises a base structure substantially rectangular in shape, with side walls having paneled effects produced by narrow continuous rounded grooves substantially rectangular in outline inclosing a centrally disposed oblong plate-like surface; such grooves having rounded corner portions, and a substantially flat top with rounded corners; such top partially overhanging the side walls. Each side wall of the structure has ornamental projections with circular bases directly adjacent the walls and rounded heads extending beyond said circular bases. The top is provided with simi-

lar ornamental projections at the corners, with a substantially circular plate adjacent the center of the same having radiating projections, while the bottom edges of the side walls have arched recesses at or substantially near their center. Surmounting the top of the base portion of the fountain is a curved arm structure extending from an ornamental base element mounted on said top and having at its upper end a rectangular shell from which an ornamental tube depends and from the top of which a bent arm terminating in a ball extends toward the front. Surmounting said rectangular box-like portion is an ornamental shell having a bulging central part upon which is mounted a syrup jar semi-spherical in shape, surmounted by an ornamental cap.

I claim:

The ornamental design for a liquid dispensing fountain as shown and described.

FRANK W. CALVERT.
